STAND FOR DISPLAYING MERCHANDISE

Andelfo J. Russo, Blauvelt, N.Y., assignor to Cadillac Wire Corp., Yonkers, N.Y., a corporation of New York and Henschel-Steinau, Jr., Fort Lee, N.J., a partnership

Filed Dec. 17, 1962, Ser. No. 72,867

Term of patent 14 years

(Cl. D80—9)

FIG. 1.

FIG. 2.

FIG. 3.

FIG. 4.

FIG. 1 is a perspective view of a stand for displaying merchandise embodying my new design;

FIG. 2 is a side elevational view thereof;

FIG. 3 is a bottom plan view thereof; and

FIG. 4 is a top plan view of the same.

I claim:

The ornamental design for a stand for displaying merchandise, as shown.
